corporation of Delaware

Application February 11, 1932, Serial No. 592,290
Renewed July 27, 1932

10 Claims. (Cl. 123—148)

This invention relates to ignition apparatus for internal combustion engines and more particularly to two cylinder engines. It is an object of the present invention to provide an ignition timer 5 distributor unit which operates at less than engine speed and which has a symmetrical arrangement of distributor head inserts or terminal posts.

Further objects and advantages of the present 10 invention will be apparent from the following description, reference being had to the accompanying drawing, wherein a preferred embodiment of one form of the present invention is clearly shown.

15 In the drawing:

Fig. 1 is a wiring diagram of an ignition circuit embodying the present invention, and employing a single circuit breaker lever.

Fig. 2 is a modified form of the invention in 20 which two circuit breaker levers operated alternately are provided.

Referring to Fig. 1, 20 designates a battery grounded at 21 connected by a switch 22 with the primary winding 23 of an ignition coil 24 25 having secondary winding 25. The primary 23 is connected with an ignition timer terminal 26 connected by a leaf spring conductor 27 with a circuit breaker lever 28 carrying contact 29 co-operating with a grounded contact 30. The leaf 30 spring conductor 27 urges the contact 29 toward the contact 30 and a rubbing block 31 carried by the lever 28 toward a cam 32 having its six lobes marked L1 to L6 respectively. A condenser 34 parallels the contacts 29 and 30.

35 The cam 32 is driven by a shaft 33 indicated by dot-and-dash lines which runs at $\frac{1}{3}$ engine speed for a two cycle engine and $\frac{1}{6}$ engine speed for a four cycle engine. The shaft 33 drives a distributor rotor block 40 carrying a three-branch 40 rotor 41 whose branches are marked R1, R2 and R3 respectively. These branches are provided with extensions 42 to take care of rotation of the engine in either direction. The secondary 45 25 is connected by wire 43 with a circuit button 44 bearing against the rotor conductor 41. The ends of rotor arms R1, R2 and R3 move past two diametrically opposite posts 45 connected respectively with the spark gaps 46 of cylinders #1 and #2, respectively.

50 It will be noted that the cam has six lobes spaced 60° and that the rotor has three branches spaced 120° . Therefore, during $\frac{1}{3}$ revolution of the shaft 33 which will occur during one crank shaft rotation of a two cycle engine or during 55 two crank shaft rotations of a four cycle engine,

the rubbing block 31 will be engaged by two cam lobes to effect two separations of the pairs of contacts 29 and 30 and hence two discharges of the ignition coil 24. At the instant of separation of contacts 29 and 30 one of the branches of rotor 30 conductor 41 will be opposite a post 45 and at the following instant of separation of contacts 29 and 30 another rotor branch will be opposite the other distributor post 45.

The operation of the distributor with respect 65 to the timer can be best understood by the use of indicia applied to two posts 45. The indicia 1—L1—R1 and the indicia 2—L2—R2 not enclosed by parentheses or brackets indicates the operation during the first third revolution of the 70 shaft 33. The lobe L1 engages the block 31 to separate the timer contacts. At this instant a sparking impulse will be distributed by rotor R1 to the left hand post 45 to supply a sparking impulse to the gap 46 in cylinder #1. This fact 75 is represented by the indicia 1—L1—R1, which means that cylinder #1 is provided with a sparking impulse caused by the engagement of cam lobe L1 with the rubbing block and this sparking impulse is distributed through rotor R1. After 80 a further rotation of 180° of the engine shaft of the two cycle engine or after a further rotation of 360° of crank shaft rotation of a four cycle engine, the lobe L2 will engage the rubbing block and the rotor R2 will be adjacent the right hand 85 end of the distributor post 45. The indicia 2—L2—R2 means that the lobe L2 controls the discharge of a sparking impulse which is distributed by rotor R2 to the spark plug of cylinder 90 #2.

The indicia (1—L3—R3) and (2—L4—R1) represent what occurs during the next third revolution of the shaft 33 or during the next cycle of operation of the engine. First, the discharge 95 of a sparking impulse is controlled by lobe L3 and this spark impulse is conducted through rotor branch R3 to the left hand post 45 and thence conducted to the spark plug of cylinder #1. Next the lobe L4 engages the rubbing block to effect the discharge of a sparking impulse 100 which is conducted by rotor R1 to the right hand post 45 and thence conducted to the spark plug of cylinder #2.

The indicia [1—L5—R2] and [2—L6—R3] represents the manner of effecting the discharge of 105 sparking impulses and the discharge of the same during the next third revolution of the shaft 33 or during the next engine cycle. The indicia [1—L5—R2] represents that the cam lobe L5 has effected the discharge of the sparking impulse 110

which rotor branch R2 distributes to the left hand post 45 connected with the spark plug of cylinder #1. The indicia [2—L6—R3] represents that the cam lobe L6 has effected the discharge of a sparking impulse which is distributed by rotor branch R3 to the right hand post 45 connected with a spark plug of cylinder #2.

Thus the ignition timer cam effects during one rotation of the shaft 33 and during three cycles 10 of engine operation, the discharge of six sparking impulses, two impulses per cycle, and these 15 sparking impulses are distributed by the three rotor branches R1, R2 and R3 operating in recurrent sequence and alternately with respect to 20 the right and left hand posts 45. It will be noted that during one revolution of shaft 33 the three branches R1, R2 and R3 are operative in sequence twice during the one revolution of the shaft 33.

20 The form of timer shown in Fig. 1 is preferable for an engine which is not required to operate at very high speeds. For a very high speed engine, the form shown in Fig. 2 is preferable 25 since two alternately operating parallel circuit breakers in series with the ignition coil are employed. These circuit breakers are designated in their entirety by reference characters A1 and A2. The circuit breaker A1 comprises contacts 30 and 51 connected respectively with a circuit breaker lever 52 and with a grounded bracket 53. The lever 52 is connected by a leaf spring conductor 54 with a terminal 55 connected by wire 56 with a wire 57 connected with the ignition primary 23. The spring 54 urges the contact 50 toward the contact 51 and a rubbing block 58 toward a cam 59 having lobes L1, L2, and L3.

The circuit breaker A2 includes contacts 60 and 61 connected respectively with circuit breaker lever 62 and ground bracket 63. The lever 62 is 40 connected by a leaf spring conductor 64 with a terminal 65 connected by wire 66 connected by the wire 57. The conductor 64 urges the contact 60 toward the contact 61 and a rubbing block 68 toward the cam 59.

45 Rubbing blocks 58 and 68 are located diametrically opposite each other and the cam is a three lobe, symmetrical cam. The cam is so constructed and arranged with respect to the rubbing blocks 58 and 68 that each pair of contacts opens while the other pair of contacts is held open in order that the circuit breakers A1 and A2 may operate alternately to effect the discharge of the coil 24. The rotor block 40 and the rotor conductor 41 are practically the same 55 as correspondingly numbered parts of Fig. 1. The indicia applied to the distributor posts 45 in Fig. 2 have the same significance in Fig. 2 as corresponding indicia have with respect to posts 45 in Fig. 1. Therefore no detailed explanation of these indicia is given other than to state that the character A1 of the indicia applied to the left hand post 45 of Fig. 2 indicates the operation of circuit breaker A1 to effect the discharge of sparking impulses distributed to the left hand post 45, and that the character A2 of the indicia applied to the right hand post 45 of Fig. 2 indicates that the circuit breaker A2 is operative to effect the discharge of sparking impulses distributed to right hand post 45 of 65 Fig. 2. In Fig. 2, as in Fig. 1, the rotor branches R1, R2 and R3 operate in recurrent sequence alternately to distribute sparking impulses to posts 45.

The two illustrated embodiments of the present invention are for two cylinder engines which

fire symmetrically, that is, every 180° of crank shaft rotation for a two cycle engine and every 360° of crank shaft rotation for a four cycle engine. This invention can be applied to engines having unsymmetrical firing order simply 80 by providing nonsymmetrical timer cams and by locating the distributor posts 45 in a correspondingly nonsymmetrical arrangement.

It is apparent from the foregoing description of the construction and mode of operation of ignition apparatus embodying the present invention that the present invention contemplates a distributor head having a center terminal and circularly arranged posts equal to N, the number of explosion periods occurring during an engine cycle, said circularly arranged posts being connected respectively to engine spark gaps, and a distributor rotor connected with the center terminal and having N+1 branches or arms, said arms moving past said posts and said arms and posts being so arranged that a group of a plurality of arms less than the total number of arms serves alternately during one engine cycle and then another group of arms including an arm not operative during the preceding cycle, serves alternately during the succeeding cycle, and so on until the rotor cycle is complete. The rotor is turned

$$\frac{1}{N+1}$$

revolution during each engine cycle. The induction means which supplies the center contact with a sparking impulse each time a rotor arm 110 is adjacent a post is controlled by a circuit interrupter means so constructed and arranged as to give a sparking impulse for each

$$S^\circ = \frac{360^\circ}{N^2 + N}$$

of rotor rotation. (The term

$$S^\circ = \frac{360^\circ}{N^2 + N}$$

is derived by subtracting from spark gap post spacing

$$\frac{360^\circ}{N}$$

the rotor arm spacing

$$\frac{360^\circ}{N+1}$$

The circuit interrupter means comprises B circuit breakers operated upon alternately by a cam rotated at rotor speed and having its lobes equal to L which equals

$$\frac{360}{BS}$$

B being a number such that the quotient of

$$\frac{360}{BS}$$

is an integer. The following tabulation shows the values of S, B and L for engines having dif- 150

ferent numbers, N , of explosion periods during each engine cycle:

5 Explosion periods during each engine cycle N	No. of rotor branches $N+1$	Sparking interval in degrees of rotation of rotor $S = \frac{360}{N+1}$	Ratio of rotor speed to engine cycle speed $\frac{1}{N+1}$	Number of cam lobes $L = \frac{360}{BS}$					
				$B = \text{No. of breakers operating alternately}$					
10				$(B=1)$	$(B=2)$	$(B=3)$	$(B=4)$	$(B=5)$	$(B=6)$
1	2	180°	1/2	2	1	—	—	—	—
2	3	60°	1/3	6	3	2	—	—	1
3	4	30°	1/4	12	6	4	3	2	—
4	5	18°	1/5	20	10	5	4	3	2
15	5	12°	1/6	30	15	10	6	5	4
6	7	8 4/7°	1/7	42	21	14	—	6	5
7	8	6 3/7°	1/8	56	28	—	14	—	7
8	9	5°	1/9	72	36	24	18	—	12
9	10	4°	1/10	90	45	30	—	18	15

20 While the form of embodiment of the present invention as herein disclosed constitutes a preferred form, it is to be understood that other forms might be adopted, all coming within the scope of the claims which follow.

25 What is claimed is as follows.

1. Ignition apparatus for a two cylinder engine comprising, in combination, means for producing sparking impulses one at each firing instant, and means for distributing the impulses comprising two distributor posts connected, respectively, with the engine spark gaps and a rotor having three branches which operate in recurrent sequence and alternately with respect to the distributor posts, said rotor being driven at such speed that it turns one-third of a revolution during each cycle of engine operation.

2. Ignition apparatus for a two cylinder symmetrical engine comprising, in combination, a 30 shaft driven at such speed that it turns one-third of a revolution during each cycle of engine operation, a six lobe cam driven by the shaft, a circuit breaker controlling an ignition coil and operated upon by the cam, and a distributor comprising two diametrically opposite posts connected, respectively, with the engine spark gaps, and a three branch rotor driven by said shaft for distributing sparking impulses alternately to said posts.

3. Ignition apparatus for a two cylinder symmetrical engine comprising, in combination, a shaft driven at such speed that it turns one-third of a revolution during each cycle of engine operation, a three lobe cam driven by the 45 shaft, two circuit breakers operated alternately by the cam for controlling an ignition coil, and a distributor comprising two diametrically opposite posts connected, respectively, with the engine spark gaps, and a three branch rotor driven by said shaft for distributing sparking impulses alternately to said posts.

4. Ignition apparatus for internal combustion engines having N explosion periods during an engine cycle comprising, in combination, a distributor head having a center terminal and N circularly arranged posts connected respectively to engine spark gaps and a distributor rotor connected with the center terminal and having $N+1$ branches or arms moving past said posts, 50 said arms and posts being so arranged that a group of a plurality of arms less than the total number of arms serves alternately during one engine cycle, and another group of arms including an arm not operative during the preceding cycle serves alternately during the succeeding cycle, and so on until the rotor cycle is complete, means for turning the rotor

cycle, and so on until the rotor cycle is complete, means for turning the rotor

$$\frac{1}{N+1}$$

80

revolution during each engine cycle, and means for providing the center contact with a sparking impulse each time a rotor arm is adjacent a post.

5. Ignition apparatus for internal combustion engines having two explosion periods during each engine cycle comprising in combination, a distributor head having a center terminal and two circularly arranged posts connected respectively with spark gaps and a distributing rotor having three branches or arms moving past said posts, said arms and posts being so arranged that, during one engine cycle, two arms operate alternately and that, during the next engine cycle, two arms including one not operating during the preceding cycle operate alternately, and so on until the rotor makes one complete cycle, means for turning the rotor at the rate of $\frac{1}{3}$ revolution during each engine cycle, and means for providing the center contact with a sparking impulse each time a rotor arm is adjacent a post.

6. Ignition apparatus for internal combustion engines having N explosion periods during an engine cycle comprising, in combination, a distributor head having a center terminal and N circularly arranged posts connected respectively to engine spark gaps and a distributor rotor connected with the center terminal and having $N+1$ branches or arms moving past said posts, said arms and posts being so arranged that the arms serve in recurrent sequence and but once during each engine cycle, the sequence being their order of arrangement, means for turning the rotor

100

105

110

115

$$\frac{1}{N+1}$$

revolution during each engine cycle, and means for providing the center contact with a sparking impulse each time a rotor arm is adjacent a post.

7. Ignition apparatus for internal combustion engines having N explosion periods during an engine cycle comprising, in combination, a distributor head having a center terminal and N circularly arranged posts connected respectively to engine spark gaps and a distributing rotor connected with the center terminal and having $N+1$ branches or arms moving past said posts, said arms and posts being so arranged that a group of a plurality of arms less than the total number of arms serves alternately during one engine cycle, and another group of arms including an arm not operative during the preceding cycle serves alternately during the succeeding cycle, and so on until the rotor cycle is complete, means for turning the rotor

120

125

130

135

$$\frac{1}{N+1}$$

140

revolution during each engine cycle, induction means for generating sparking impulses and circuit interrupter means for causing a sparking impulse to be provided at the center terminal each time a rotor arm is adjacent a post, said interrupter means comprising B circuit breakers operated alternately by a cam having

$$\frac{360}{BS}$$

150

cam lobes and rotated by the engine at the rate of

$$\frac{1}{N+1}$$

5

revolution during each engine cycle, S being the sparking interval in degrees of rotor rotation and equal to

$$10 \quad \frac{360^\circ}{N^2+N}$$

and B being a number such that the quotient of

$$15 \quad \frac{360}{BS}$$

is an integer.

8. Ignition apparatus for internal combustion engines having N explosion periods during an engine cycle comprising, in combination, a distributor head having a center terminal and N circularly arranged posts connected respectively to engine spark gaps and a distributor rotor connected with the center terminal and having N+1 branches or arms moving past said posts, said arms and posts being so arranged that the arms function alternately but each not more than once in succession during an engine cycle and that those posts which are served by a certain arm during a certain engine cycle are served by another arm during the next engine cycle, means for turning the rotor

$$20 \quad \frac{1}{N+1}$$

revolution during each engine cycle, and means for providing the center contact with a sparking impulse each time a rotor arm is adjacent a post.

9. Ignition apparatus for an engine having N explosion periods during each engine cycle com-

prising, in combination, a distributor comprising a head having a center terminal and N posts connected respectively with N engine spark gaps and a rotor having N+1 connected arms rotating past the posts at the rate of

$$80 \quad \frac{1}{N+1}$$

revolution during each engine cycle, and means for providing a sparking impulse when a rotor arm is adjacent to a post.

10. Ignition apparatus for an engine having N explosion periods during each engine cycle comprising, in combination, a distributor comprising a head having a center terminal and N equiangularly spaced posts connected respectively with N engine spark gaps and a rotor having N+1 equiangularly spaced connected arms rotating past the posts at the rate of

$$90 \quad \frac{1}{N+1}$$

revolutions during each engine cycle, and means for generating a sparking impulse each

$$95 \quad S^\circ = \frac{360^\circ}{N^2+N}$$

of rotor rotation, said means including B circuit breakers operated alternately by a cam rotating at rotor speed and having L lobes equal to

$$100 \quad \frac{360}{BS}$$

B being a number such that the quotient of

$$110 \quad \frac{360}{BS}$$

is an integer.
